Attorney.

UNITED STATES PATENT OFFICE

CLAUDE SÉRY, OF AIX-EN-PROVENCE, FRANCE, ASSIGNOR TO SOCIÉTÉ À RESPONSABILITÉ LIMITÉE "ÉTABLISSEMENTS ROTATISS," OF PARIS, FRANCE, A FRENCH COMPANY

CIRCULAR-WEAVING LOOM

Application filed February 23, 1929, Serial No. 342,209, and in France March 6, 1928.

My invention relates to a selector mechanism for circular weaving looms of the kind in which the selector only imparts to the warp threads a limited initial motion, the 5 shuttle being provided with means adapted to complete this motion.

The mechanism according to my invention comprises an electro-magnet for each warp thread, the armature of said magnet being 10 provided with thread guiding means.

In the annexed drawings:

Fig. 1 is a diagrammatical radial section of a circular weaving loom having a selector according to my invention.

15 Fig. 2 is a section on line II—II of Fig. 1.

Fig. 3 is a fragmental plan view of a card adapted to control the electromagnets of the loom.

Referring to Figs. 1 and 2, 34 is the other 20 cylindrical member of the loom, having a groove 210 in which slide the outer skates of the shuttles. The latter are provided with separating cams 38 adapted to complete the warp thread movements, as will be described 25 later on.

The warp threads such as 89 extend radially with respect to the loom axis. They are guided by fixed guides 75 from which they pass through a movable guide 92 fixed to a 30 spring 94 having its end fixed to member 34 at 211. Spring 94 also carries an armature 93 under which is placed an electromagnet 95 fixed onto a flange 35 integral with member 34. A slit 212 permits the passage of thread 35 89, as shown.

When spring 94 is free (i. e. when no current flows through electromagnet 95), the armature 92 is at its uppermost position, shown in full lines Fig. 1 and the thread 89 is somewhat over the plane of the tips of the cams 38 of the shuttles. The thread is thus lifted by the cam of the first incoming shuttle and passes over the same.

When electromagnet 95 is energized, the 45 thread is lowered below the tips of cams 38 and passes under the same, as it will be readily understood.

The control of the electromagnets of the loom is preferably effected, as shown, by 50 means of spring contacts such as 97 cooperat-

ing with fixed contacts 96 and provided with projections 98 under which passes a card 99 having perforations corresponding to the projections 98. When one projection 98 is over a perforation of card 99, the corresponding spring 97 is free and the circuit of the corresponding electromagnet is interrupted. On the contrary, when a projection 98 is not over a perforation, the corresponding spring 97 is maintained in contact with terminal 96 and the corresponding electromagnet is energized.

The card 99 may be driven by any suitable mechanism.

I claim:

1. In circular weaving looms of the kind in which the warp threads are given a small initial motion which is completed by means carried by the shuttles, a selector mechanism comprising movable thread guides through 50 which the warp threads are passed, and fixed electro-magnets adapted to actuate said thread guides without at the same time actuating the warp thread bobbins.

2. A selector mechanism as claimed in 75 claim 1, comprising for each warp thread a thread guide; a spring support to which said thread guide is fixed; an armature also fixed to said spring support; and an electromagnet adapted to actuate said armature, said spring 80 support being adjusted in such a way that, at the free position thereof, said thread guide guides the warp thread over the shuttles and, on the contrary, at the depressed position thereof, said thread guide guides the warp 85 thread under the shuttles.

3. A selector mechanism as claimed in 90 claim 1, wherein the electromagnets of the loom are energized through switches actuated by perforated cards.

In testimony thereof I affix my signature.

CLAUDE SÉRY.
